(57) **CLAIM**

The ornamental design for a bubble wand handle, as shown and described.

DESCRIPTION

FIG. 1 is a front view of the bubble wand handle;
FIG. 2 is a back view of the bubble wand handle;
FIG. 3 is a left side view of the bubble wand handle;
FIG. 4 is a right side view of the bubble wand handle;
FIG. 5 is a bottom view of the bubble wand handle;
FIG. 6 is a top view of the bubble wand handle;
FIG. 7 is a top, front, right side perspective view of the bubble wand handle; and,
FIG. 8 is a bottom, back right side perspective view of the bubble wand handle.

The broken lines show portions of the bubble wand handle that form no part of the claimed design.

1 Claim, 8 Drawing Sheets
